HENRY HASSENPLUG, OF HUNTINGDON, PENNSYLVANIA, ASSIGNOR
TO HIMSELF AND EDWARD HASSENPLUG.

Letters Patent No. 65,217, dated May 28, 1867.

IMPROVEMENT IN SAWING MACHINES.

The Schedule referred to in these Letters Patent and making part of the same.

TO ALL WHOM IT MAY CONCERN:

Be it known that I, HENRY HASSENPLUG, of Huntingdon, in the county of Huntingdon, and State of Pennsylvania, have invented a new and improved Sawing Machine; and I do hereby declare that the following is a full, clear, and exact description thereof, which will enable others skilled in the art to make and use the same, reference being had to the accompanying drawings, forming part of this specification, in which—

Figure 1 is a vertical longitudinal section of my improved sawing machine, taken on the line *x x*, fig. 2.

Figure 2 is a plan or top view of the same.

Similar letters of reference indicate like parts.

This invention relates to a portable sawing machine, which is to be chiefly used for cross-cutting and for cutting cord-wood, and for scroll-work, but which may also be changed so as to be used for ripping.

The invention consists chiefly in the self-feeding apparatus, whereby the wood is gradually fed to the vertical reciprocating saw. The invention also consists in such a construction of the parts that the distance between the ends and the fulcrum of the lever by which the saw is operated can be changed at will, so as to increase or diminish the power or the speed of the machine, as may be desired.

A represents an oblong frame, made of wood or other suitable material, and supported by posts, *B B*, of suitable construction. The same is provided with suitable braces for strengthening, and has two handles, *a a*, at one end, and a wheel, *b*, at the other end, so that the whole machine may be moved from place to place like a wheelbarrow by raising the ends *a*. An upright post, *C*, is arranged in the frame *A*, and extends above the same, as shown. Two levers, *D* and *E*, are pivoted to the post *C*, the pins *c* and *d* forming their respective fulcra. To the front end of each of these levers is secured the end of an upright saw, *F*, and the rear ends of the levers are pulled together by a piece of cord, *e*, that is provided with a lever, *e'*, in the usual style for straining or stretching the saw-blade. *G* is the carriage, upon which the block to be sawed is placed. A cross-head or rest, *f*, is provided thereon for the block to rest against, and a curved lever, *g*, which is provided with teeth at its under side, and which is pivoted to the rear or inner end of the carriage. *G* serves to hold the said block in place; the front end of said lever *g* being held down by a chain, *h*, which is fitted over a pin, *i*, that is secured to the front edge of the carriage, as is clearly shown in fig. 1. The carriage is placed upon rests or flanges, *j*, which are arranged stationary on the frame *A*, so that the carriage can freely slide to and from the saw; and the carriage is slotted so as to let the saw pass freely up and down. A cord or chain, *l*, is attached to the rear or inner end of the carriage *G*, and passes over a roller, *m*; that is secured to the rear end of the frame *A*, and is provided at its end with a weight, *n*. Before the wood is secured upon the carriage the latter is prevented from sliding back towards the saw by a pin, *o*, or other suitable stop. When the wood is secured this stop is removed, and the weight *n* instantly pulls the carriage back until the front or cutting edge of the saw strikes against the wood. Then the motion is imparted to the levers *D* and *E*, or to one of them only, and the saw is moved up and down, and the carriage is gradually fed back by a weighted pawl, *p*, that is pivoted to the lever *D*, and engages a ratchet-bar, *q*, which is fixed in the upper surface of the carriage *G*, as shown. During the vibrating motion of the lever *D* the end of the lever *p* is moved back and forth, and during its back move it carries the carriage and block back with it.

Motion is imparted to the lever *D* by a connecting-rod, *H*, which is secured to a crank-shaft, *I*, the latter receiving motion from any suitable mechanism. The upper end of the rod *H* is hinged to a small pin, *r*, which passes through the lever *D*. It will be observed that the levers *D* and *E* are provided with a series of holes, *s s'*, whereby their respective fulcra can be changed when desired, which is obvious, as is also the object of the holes *t* in the rear end of the lever *D*, whereby the position of the rod *H* can be changed. It will be seen that a great change of speed and power can thus be obtained for this machine, and the same can consequently be adapted for different kinds of work. The front end of the lever *E* is connected with the end of a spring, *u*, or provided with a weight, *v*, or both, which have the tendency to depress the front end of this lever. The object of this spring and weight is to force the saw through the wood during the downward stroke of the former, while the upward stroke is not affected. By having two posts, *C*, and connecting two sets of levers, *D* and *E*,

by cross-bars, to which the saw is attached, this same machine may be adapted for ripping, and for doing all other kinds of work that can be done on a sawing machine. In this case the perforated levers, the feed motion, and the weight *v* or spring *u* would operate as described for the cross-cut saw.

What I claim as new, and desire to secure by Letters Patent, is—

The feed device, consisting of the weighted cord *l*, arranged in relation with the pawl *p* and ratchet-bar *q*, all made as described, and operating so that the carriage shall be moved toward the saw, as herein set forth for the purpose specified.

HENRY HASSENPFUG.
